UNITED STATES PATENT OFFICE.

CHARLES R. MILLER AND TEXAL ARMOY KEY, OF WHITESBORO, TEXAS.

MEAT-SLICER.

1,214,939.

Specification of Letters Patent.

Patented Feb. 6, 1917.

Application filed June 1, 1915. Serial No. 31,567.

To all whom it may concern:

Be it known that we, CHARLES R. MILLER and TEXAL ARMOY KEY, citizens of the United States, residing at Whitesboro, in the county of Grayson, State of Texas, have invented a new and useful Meat-Slicer, of which the following is a specification.

The device forming the subject matter of this application is adapted to be employed for cutting meat, and one object of the invention is to provide novel means for retaining in place, the lead screw whereby the feeding member is actuated.

Another object of the invention is to provide novel means for retaining the guides on which the feed member slides.

Another object of the invention is to provide a structure of the type above mentioned embodying an audible alarm whereby the operator may be advised when he has advanced the meat through a predetermined step.

Another object of the invention is to improve the cutting member and its mounting.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing:—

Figure 1 shows the invention in top plan; Fig. 2 is an end elevation;

Fig. 3 is an end elevation wherein the table and the cutting mechanism disclosed in Fig. 2 has been removed;

Fig. 4 is a transverse section;

Fig. 5 is a fragmental transverse section showing the audible alarm;

Fig. 6 is a fragmental horizontal section wherein parts are broken away.

In carrying out the invention there is provided a platform 1 supported on end walls or feet 2 and 3. Extended longitudinally of the platform 1 adjacent one edge thereof is a guide 4 for the material to be cut, the guide comprising ears 5 united by means of securing elements 6 with the platform 1. The

foot 3 is provided with openings 7 and 8 therethrough. In the foot 2 there is formed an opening 9 and upon either side of the opening 9, seats 10 are formed in the inner face of the foot 2. One end of a lead screw 11 is journaled for rotation in the opening 7, the other end of the lead screw terminating in a reduced neck 12 journaled in the opening 9 and defining a shoulder 14 cooperating with the inner face of the foot 2. Any suitable means may be provided for rotating the lead screw 11. In the present form, but not necessarily, a crank 16 is assembled with the neck 12 of the lead screw. Located on opposite sides of the lead screw 11 are guides 15, each guide at one end being mounted in one of the openings 8, the other ends of the guides being received in the seats 10. Referring to Fig. 6 of the drawings it will be understood that the guides 15 may be mounted in place by sliding them to the left through the openings 8 in the foot 3, until the left hand ends of the guides are received in the seats 10 of the foot 2, a similar operation being carried out in the case of the lead screw 11, the reduced neck 12 of the lead screw passing through the opening 9, the shoulder 14 abutting against the inner face of the foot 2, and the opposite end of the lead screw being received in the opening 7 of the foot 3.

The invention comprises a table 17 adapted to receive the meat after the same is sliced, the table 17 being depressed slightly below the platform 1. The table 17 embodies an end flange 18 and side flanges 26. The end flange 18 abuts against the outer face of the foot 3 and is held thereto by securing elements 19. It will now be understood that the flange 18 of the table 17 constitutes a means for maintaining in place the guides 15 and the lead screw 11—all of which will be obvious from Fig. 6.

The invention comprises a feed member in the form of a plate 20, mounted to move along the platform 1 and embodying a reduced neck 21 passing through a longitudinal slot 22 in the platform. The lower end of the neck is equipped with a laterally enlarged nut 23 bearing against the under face of the platform 1. The lead screw 11 is threaded into the intermediate portion of the nut 23, the end portions of the nut being slidably mounted on the guides 15.

Pairs of uprights 24 are united by means of securing elements 25 with the side flanges

26 of the table 17. The invention comprises a cutter including a frame 28 mounted to move vertically and in the direction of its length between uprights 24 of the respective 5 pairs. One end of the frame 28 is provided with a handle 29 and the other end of the frame is provided with a tightening device 30. A thin, flexible blade 31 is provided, one end of the blade being detachably assembled as shown at 32 with the handle, and the blade being detachably connected as shown at 33 with the tightening device 30. The frame 28 of the cutter moves between the uprights 24 and serves to guide and direct the movement of the cutter, the blade 31 moving along the outer edges of opposed uprights 24. Obviously, by manipulating the tightening device 30, the flexible blade 31 may be tightened up and made to exercise 10 its function.

The invention comprises an audible alarm whereby the operator may be advised when he has advanced the meat to be cut, through a predetermined distance. In the present 25 embodiment of the invention, the audible alarm embodies a ratchet wheel 34 secured to the lead screw 11, a pawl 35 being adapted to coact with the ratchet wheel, the pawl being pivoted to the foot 2 and being extended 30 upwardly through a slot 37 formed in the platform 1. Connected to the foot 2 and to the pawl 35 is a spring 36 which maintains the pawl in operative relation to the ratchet wheel.

35 In practical operation, the meat to be cut is placed upon the platform 1 and, when the lead screw 11 is rotated by means of the crank 16 or its equivalent, the feed member 20 will be advanced, carrying with it the 40 meat to be cut. Whenever a rotary movement is given to the lead screw 11, the pawl 35 will drop down off one of the shoulders on the ratchet wheel 34, thus producing a click which the operator can readily hear, 45 the operator thus being guided and directed as to the distance through which he has ad-

vanced the meat by the manipulation of the lead screw 11.

The cutter 28-31 may be reciprocated and moved vertically, to slice the meat, the 50 slices dropping onto the table 17. In order to prevent an injury to the blade 31, caused by the latter coming into contact with the table 17, stops 27 may be held between the uprights 24, the stops 27 coacting with the 55 frame portion 28 of the cutter to limit the downward movement thereof.

Having thus described the invention, what is claimed is:—

1. In a device of the class described, a 60 platform; opposed pairs of uprights standing above the platform; a cutter comprising a rigid frame having laterally offset ends, a flexible blade, and means for connecting the blade terminally with the offset 65 ends of the frame, one of said means being a tightening device for the blade; the frame being received between the uprights of the pairs to guide the cutter independently of the blade and to prevent a flexing of the 70 blade.

2. In a meat cutter, a platform provided with depending feet; a lead screw journaled in the feet and provided with a shoulder engaging one foot; a guide abutting against 75 said foot and received in the other foot; a table secured to the last specified foot and constituting means for maintaining the lead screw and the guide assembled with the feet; a cutter operating adjacent the table; and 80 a feed member into which the lead screw is threaded, the feed member being mounted to reciprocate on the guide.

In testimony that we claim the foregoing as our own, we have hereto affixed our signatures in the presence of two witnesses. 85
